UNITED STATES PATENT OFFICE

2,535,631

SHEET METAL CUTTING TOOL

Charles B. Gray, Springfield, Pa.

Application December 16, 1944, Serial No. 568,509

9 Claims. (Cl. 30—241)

1

This invention relates generally to a metal cutting tool and more particularly to certain improvements in the construction of a portable, hand-held sheet metal cutting tool of the nibbler type such as is disclosed in my prior United States Letters Patent Nos. 2,278,174 and 2,278,311, both granted on March 31, 1942.

Among the principal objects of the present invention is to provide an improved construction of and mounting for the die which coacts with the reciprocating punch or coacting element of the tool for cutting out of the sheet metal or other material being cut a successive series of chips or slugs to slit the work along a given line. It is essential in tools of this character that the die be held firmly in position in order to provide for the most efficient cutting action for the tool and in order to prevent premature wear of both the punch and the die. In order to insure the attainment of this desired objective, the present invention provides a form of die and mounting therefor which facilitates and insures such securement of the die in operative position that it is relatively immovable with respect to the reciprocating punch during all conditions of use of the tool, the mounting arrangement being such, however, that the die may be readily removed for servicing, inspection or replacement without disturbing any other parts of the assembled nibbling tool.

A further and important object of the present invention is to provide the nibbling tool with an improved construction of stripper which serves the dual purpose of holding the cutting blade of the reciprocating punch firmly against its supporting backing and of stripping the stock from the punch on the return stroke of the latter. In use of the nibbling tool it is frequently necessary to vary the adjustment of the stripper both as respects its pressure against the cutting blade of the reciprocating punch and the extent of its spacing from the die required to be varied depending upon the gauge and hardness of the sheet material to be cut by the nibbling tool and accordingly, it is an object of the present invention to facilitate ready adjustment of the stripper in both of the foregoing respects.

In addition to the foregoing, it is an object of the present invention to provide arrangements of a removable die and a readily adjustable stripper which are simple and inexpensive to manufacture and incorporate in the nibbling tool and which, at the same time, are of such design and construction as not to obscure from the view of the operator the line along which the work is to be cut.

2

Other objects and advantages of the invention will appear more fully hereinafter, it being understood that the present invention consists substantially in the combination, construction, location and relative arrangement of parts, all as will be described more fully hereinafter, as shown in the accompanying drawings and as finally pointed out in the appended claims.

In the said accompanying drawing, which illustrates a preferred construction of the parts of the present invention:

Figure 1 is a side view showing partly in elevation and partly in vertical cross-section a tool construction in accordance with and embodying the principles of the present invention;

Figure 2 is a front view of the operating head of the tool with the front cover thereof removed;

Figure 3 is a perspective view of the punch-guiding and die-supporting member showing the die secured in position thereon;

Figure 4 is a side elevational view of the assembly shown in perspective in Figure 3;

Figure 5 is a bottom plan view of such assembly;

Figure 6 is a sectional view taken on the line 6—6 of Figure 4; and

Figure 7 is a side elevational view of a key such as may be employed in cooperation with the motor shaft of the tool for raising or lowering the punch with respect to its die.

Referring now to the drawings, it will be observed that the nibbling tool of the present invention is of a form and construction adapted to be conveniently held in the hand of the operator, the operating head of the tool, designated generally by the reference numeral 10, being secured in any suitable manner to the forward end of the casing 11 in which is housed an electric motor 12 for driving the main drive shaft 13 of the tool through the intervention of suitable gears 14.

The operating head 10 of the tool is in all material respects similar to that shown in my prior Patent No. 2,278,311 aforesaid, and includes a channel-shaped guide 15 in which is adapted to be vertically reciprocated a supporting member 16 for the punch 17. The reciprocating punch-supporting member 16 is provided in its rear face with a transverse slot or groove in which is received a shoe 18 fitted upon an eccentric 19, the said shoe being of a width less than the width of the slot in which it is fitted, but of a depth substantially equal to said slot. Thus, when the punch-supporting member 16 is properly fitted within its channel-shaped guide 15 and the eccentric shoe 18 is received within the transverse slot or groove in the back face

of the reciprocating member 16, rotation of the shaft 13 will cause the eccentric 19 to shift the shoe 18 laterally within the groove simultaneously as said shoe acts on the member 16 to effect vertical reciprocation of the latter.

Formed as an integral part of the channel-shaped guide 15 and extending downwardly from the lower extremity thereof is a channel-shaped guide 28, this latter being provided with a frontally presenting channel in continuation of the channel formed in the upper guide 15. Formed in the forward face of the reciprocating punch-supporting member 16 is a vertically extending groove within which is fitted the squared shank of the punch or cutting tool 17. A clamping block 23 overlies the squared portion of the punch 17 and is secured to the reciprocating member 16 by means of the bolts 24 to frictionally retain the punch in position against vertical displacement with respect to its supporting member 16. As in the prior patented construction, in order to provide for maximum clamping action of the clamping block against the punch, the said block is preferably provided with an inner clamp shoe 25 which is pressed against the punch by means of the set screws 26.

Vertical adjustment of the punch 17 within its reciprocating support 16 is effected by means of a screw 27 which is fitted within an interiorly threaded bore 28 in the upper end of the reciprocating member 16, this adjusting screw being arranged in vertical alinement with the punch and being adapted to engage the upper end thereof to serve not only as a fixed upper abutment for the punch, but also as a means for adjusting the punch vertically along its reciprocating axis, it being apparent that by adjusting the said screw 27 in one direction or another, a punch of given length may be positionally adjusted to present its cutting edge in more or less closely spaced relation to the cooperating die for the punch.

Fitted within the channel-shaped lower guide 20 is a combination die-supporting and feed-limiting unit, designated generally by the reference numeral 29 and shown most clearly in Figures 3 and 4. This unit 29 is in turn provided in its upper portion with a frontally presenting channel 30 which is adapted to be vertically alined with the punch-receiving groove in the reciprocating member 16 when the unit 29 is secured in position within its support 28, as shown in Figure 1. The unit 29 is securely fixed in position within the said support 28 therefor by means of a pair of screws 31-31 which are projected commonly through the base walls of the nested channeled members 20 and 29. It will thus be apparent that the channel 30 of the unit 29 serves as a fixed guide for the lower portion of the reciprocating punch 17 during reciprocation thereof in unison with its reciprocating supporting member 16.

Extending downwardly from the channeled portion 30 of the unit 29 is a part 32 of reduced cross-section, this part 32 serving not only as a backing for the lower free end of the reciprocating punch, but also as a means for limiting the feed of the work relatively to the tool. As in the prior patented construction of my tool, this depending part 32 of the unit 29 is provided with a flat frontal face 33 which is in continuation of and is disposed in the vertical plane of the rear face of the reciprocating punch 17. Also, the width of this backing 33 for the lower end of the punch is no greater than the effective width of the lat-

ter and, if desired, may be of less width than that of the punch. Further, the said punch-backing part 33 diminishes in width from front to rear thereof, particularly in the immediate vicinity of the feeding plane of the sheet metal to be cut, in consequence of which it becomes possible to cut a slot in the sheet material of a width equal to that of the punch and at the same time permit the tool as a whole to be more or less freely rotated in said slot to change the direction of the latter as circumstances may require. Thus, the tool is adapted to slit sheet material along sharply curved as well as straight lines of any independent length.

15 The construction of tool as described to this point is, as has already been indicated, quite similar in all material respects to that of my prior Patent No. 2,278,311 aforesaid. However, in the said prior patented construction, the main 20 guide for the reciprocating punch-supporting member is shown formed as an integral forward extension of the front half of a two part casing for the motor and other parts immediately associated therewith. In the present instance, this 25 main guide, herein designated by the reference numeral 15, is shown formed as an integral part of a circular plate 34 which is adapted to be secured, as by means of the bolts 35, to the flanged forward extremity of the motor housing 30. Of course, any suitable means or arrangement may be provided for mounting the operating head 10 in operative relation to the handheld motor unit without departing from the general principles of the present invention.

35 Referring now more particularly to Figures 3, 4 and 5, it will be noted that in the present construction, the punch-backing part 33 of the unit 29 is formed at its lower end with a pair of laterally spaced, forwardly projecting arms 40-36, these arms being formed as integral extensions of the depending part 32 of the guide member 29 and being separated from each other a distance equal to the width of the part 32. Also, the said arms 36-36 are each so offset 45 laterally and forwardly of their support 32 as to provide the same with co-planar horizontally disposed flat upper surfaces 37-37 and co-planar vertically disposed flat rear surfaces 38-38. The contiguous surfaces 37 and 38 of each arm 36 50 thus serve as a lateral seat for the die plate 39.

This die plate 39, as most clearly appears in Figures 3, 4 and 5, is of generally U-shape in plan to provide a pair of rearwardly extending arms 40-40 which define therebetween a notch 55 41 of a width equal to that of the cutting blade of the punch 17 and the spacing between the die-supporting arms 36-36. The rear extremities of the arms 40-40 of the die plate 39 are each downwardly turned to form lugs 42-42 60 which respectively engage the rear surfaces 38-38 of the die-supporting arms, the die plate being secured in position by means of screws 43-43 which project upwardly through the die-supporting arms 36-36 into threaded engagement with the die plate. The notch 41 of the die plate is of such length and width that when the plate is secured in position as shown in Figures 3, 4 and 5, the three walls of the notch 65 cooperate with the frontal face 33 of the depending part 32 of the combined punch guide and die-supporting member 29 to form a die opening 44 into which the lower extremity of the punch is adapted to project as it penetrates the sheet material overlying the die. It will be noted that 70 the die opening 44 is of a shape closely corre-

sponding to the cross-sectional shape of the lower cutting extremity of the reciprocable punch 17 and that the die opening is effectively maintained in exact alinement with the punch by means of the interlocking engagement of the lugs 42—42 of the die with the rear ends of the die-supporting arms 36—36, such lugs serving to prevent forward displacement of the die plate with respect to its support under the pressure exerted by the expansion of the slug pushed out of the sheet metal being cut. Free ejection of the punched out slugs is effected by way of the space 45 provided between the die-supporting arms 36—36.

It will be observed that the overall dimensions of the die and its immediately associated supporting structure are sufficiently small to permit the same to be projected through a relatively small opening preliminarily provided in the sheet metal to be cut when it is desired to cut a design or outline in the sheet metal without passing through an edge thereof. In this connection, it will be noted further that the frontal edges of the die-supporting arms 36—36 have their vertical edges chamfered or rounded, as at 46, such chamfering being continued upwardly through the die itself. Also, if desired, instead of forming the die-supporting members 36—36 as freely extending elements, as shown in Figure 3, the forward ends of said arms may be joined together by an integral bridging member, such construction being preferably obtained by forming the die-support as a solid block extending forwardly of its support 32 and then cutting an opening therethrough of a shape and form suitable to permit the free ejection of the punched out slugs, the opening so formed in the die-support being immediately below and in registry with the die opening.

Operatively associated with the punch to strip the sheet metal therefrom upon each upward stroke of the punch is a stripper 47 (see Figures 1 and 2). This stripper essentially consists of a member 48 having a main central part 49 from which depends a co-planar angularly related part 50, the lower extremity 51 of which is adapted to engage and press the relatively thin blade portion of the punch 17 against the flat surface 33 of the feed-limiting member 32 of the combined punch guide and die-support 29. The upper end of the part 49 of the stripper is provided with an integrally formed, laterally extending part 52, which latter part also extends forwardly of the frontal surface of the portion 49 of the stripper.

The stripper is mounted upon a supporting plate 53 therefor which is in turn secured, by means of the screws 54, to the body portion 20 of the operating head of the tool. This supporting plate 53 is provided to one side thereof with a raised boss 55 having a vertically extending free edge 56 which serves as a side support for the central part 49 of the stripper. This part 49 of the stripper is provided with a vertically elongated opening or slot 57 extending transversely through the body of the stripper, and a pivot pin 58 is projected therethrough and into the supporting boss 55, as at 59 (see Figure 2) to serve as a fulcrum about which the stripper may be pivotally adjusted to more or less tightly engage the reduced blade portion of the cutting tool 17. A screw 60 projects through the upper end of the stripper with its inner end engaging the supporting plate 53, as at 61 (see Figure 2), it being apparent that upon rotation of this screw 60 in clockwise direction, the stripper will be caused to

rotate about its pivot pin 58 to thereby present its lower extremity 51 in firm engagement with the cutting blade of the reciprocating tool.

The supporting plate 53 for the stripper is provided with a pair of frontally projecting lugs 61—61 which rise out of the boss 55 as integral parts thereof. Operatively associated with these lugs is a vertically extending adjusting stem 62, the upper end of which is threaded, as at 63, for projection into the transversely extending part 52 of the stripper. This adjusting stem 62 is further provided with a pair of vertically spaced integral collars 63, these collars being disposed respectively above and below the pair of lugs 61—61 at the same time that the said pair of lugs 61—61 embrace therebetween that portion of the stem which extends between its spaced collars. It will be apparent that by reason of this construction, rotation of the adjusting stem 62 in one direction or the other will effect a corresponding vertical adjustment of the stripper to thereby provide for more or less space between the lower extremity of the upper surface of the die plate 39. Of course, in effecting such vertical adjustment, the pivot pin 58 is first loosened, said pin being tightened only after the proper adjustments of the stripper, both for distance of its lower edge above the die and for pressure engagement against the blade portion of the reciprocating punch, have been effected.

As in the construction of tool described in my previously issued Patent No. 2,278,311, the moving parts of the operating head of the tool are closed by a removable cover plate 65, which is secured to the channeled main guide member 15 by means of suitable screws 66 projected into threaded apertures 67 suitably provided in said main guide member 15.

It will be apparent that in the tool as just described, the punch 17 may be adjusted axially with respect to its die opening 44 by first loosening the clamping screws 24 and 26 and then adjusting the upper adjusting screw 27 as desired. It will be understood, of course, that for proper adjustment of the punch, its upper end must be at all times in abutting contact with the inner end of the adjusting screw 27, and also that the lower end of the cutting blade of the tool must be spaced above the die a distance sufficient to clear the sheet metal to be cut by the tool when the punch is raised to the upper limit of its stroke. In order to facilitate such adjustment, the rear end of the motor shaft of the tool is squared, as at 68, to receive a key 69 (see Figure 7) by means of which the main shaft of the tool may be rotated by hand to raise the punch to its upper limit of its throw. With the punch in such position, its adjustment as well as that of the stripper may be readily effected, as hereinbefore described, to condition the tool for use on any gauge of stock to be cut within the capacity of the tool.

It will be understood, of course, that the present construction of tool as hereinbefore described is susceptible of various changes and modifications which may be made from time to time without departing from the general principles or real spirit of the present invention, and it is accordingly intended to claim the same broadly, as well as specifically, as indicated by the appended claims.

What is claimed as new and useful is:

1. In a motor-operated hand-held nibbling tool for slitting sheet material, a reciprocable punch, a relatively fixed guide for said punch having a

punch-backing part terminating at its lower end in a die support, said punch-backing part having a flat frontal face of a width not exceeding the width of the punch and of gradually reduced cross-section rearwardly of said face, said die support extending frontally of said punch-backing part and laterally to either side thereof and being provided with an opening therethrough, one edge of which is defined by a continuation of said flat face of the punch-backing part, and a die plate carried by said support, said die plate being notched to provide a pair of laterally spaced rearwardly extending arms which overlie the laterally extending portions of the die support, said arms having terminal extremities which interlock with the rear ends of the die support to prevent forward displacement of the die plate relatively to said punch-backing part.

2. In a motor-operated hand-held nibbling tool for slitting sheet material, a reciprocable punch, a relatively fixed guide for said punch having a punch-backing part terminating in a die support, said die support extending frontally of the punch-backing part and laterally to either side thereof, and a die plate disposed flatwise upon the upper surface of said die support with its marginal front and side edges substantially flush with those of the said support, said die plate being provided with rearwardly disposed depending lugs respectively adapted to engage behind the rear ends of the die support to either side of the punch-backing part whereby to prevent forward displacement of the die plate with respect to said punch-backing part, said die support being provided with an opening therethrough, the rear edge of which is coincident with the frontal face of the punch-backing part to define the rear edge of a die opening and the said die plate being notched to provide a front edge for the die opening which is spaced forwardly of the punch-backing part to a distance substantially equal to the thickness of the cutting edge of the punch.

3. In a motor-operated hand-held nibbling tool for slitting sheet material, a reciprocable punch, a relatively fixed guide for said punch having a punch-backing part terminating at its lower end in a die support, said punch-backing part having a flat frontal face of a width not exceeding the width of the punch and of gradually reduced cross-section rearwardly of said face, said die support extending frontally of said punch-backing part and laterally to either side thereof and being provided with an opening therethrough, one edge of which is defined by a continuation of said flat face of the punch-backing part, a die plate carried by said support, said die plate being notched to provide a pair of laterally spaced rearwardly extending arms which overlie the laterally extending portions of the die support and interlock with the rear ends of the latter to prevent forward displacement of the die plate relatively to said punch-backing part, and screw means extending upwardly through the die support and into the die plate for securing the same together.

4. In a motor-operated hand-held nibbling tool for slitting sheet material, a reciprocable punch, a relatively fixed guide for said punch having a punch-backing part, the frontal face of which is flat and of a width not exceeding that of the punch, a stripper operatively associated with the punch and having a part bearing against the frontal face of the punch adapted to restrain the latter from flexing outwardly and away from said punch-backing part, and screw means en-

gageable with said stripper for effecting vertical adjustment thereof upon rotation of said means in one direction or the other.

5. In a motor-operated hand-held nibbling tool for slitting sheet material, a reciprocable punch, a relatively fixed guide for said punch having a punch-backing part, a stripper of generally bell crank form mounted upon a relatively fixed pivot, means extending through the upper arm of said stripper and engageable with a fixed part of the tool to swing the stripper about its pivot whereby to cause the lower arm of said stripper to engage and press the punch against its said punch-backing part, and axially fixed rotatable means engageable with the stripper to vertically adjust the same with relation to the plane of the sheet metal to be cut.

6. In a motor-operated hand-held nibbling tool for slitting sheet material, a reciprocable punch, a relatively fixed guide for said punch having a punch-backing part, and a stripper assembly operatively associated with said reciprocable punch, said assembly including a relatively fixed plate providing a pivotal mounting for the stripper and a support for an axially fixed rotatable screw element threadedly engageable with the stripper for vertically adjusting the position of the latter upon rotation of the element in one direction or the other.

7. In a motor-operated hand-held nibbling tool for slitting sheet material, a reciprocable punch, a relatively fixed guide for said punch having a punch-backing part, a stripper assembly operatively associated with said reciprocable punch, said assembly including a relatively fixed plate providing a pivotal mounting for the stripper and a support for an axially fixed rotatable screw element threadedly engageable with the stripper for vertically adjusting the position of the latter upon rotation of the element in one direction or the other, and means associated with the stripper for positionally adjusting the same about its pivot to vary, as desired, the pressure of the stripper against the punch.

8. In a motor-operated hand-held nibbling tool for slitting sheet material, a reciprocable punch, a relatively fixed guide for said punch having a punch-backing part terminating in a die support, a die plate carried by said support, said die plate being centrally notched to provide a pair of laterally spaced arms defining therebetween a die opening, said arms being provided with terminal extremities which interlock with the rear of said die support to prevent displacement of the die plate forwardly of said punch-backing part, said arms being respectively in engagement with opposite sides of the said punch-backing part to prevent lateral displacement of the die plate with respect to said part.

9. In a motor-operated hand-held nibbling tool for slitting sheet material, a reciprocable punch, a relatively fixed guide for said punch having a punch-backing part terminating at its lower end in a die support, said punch-backing part having a flat frontal face of a width not exceeding the width of the punch and of gradually reduced cross-section rearwardly of said face, said die support extending frontally of said punch-backing part and laterally to either side thereof and being provided with an opening therethrough, one edge of said opening being disposed in the vertical plane of the flat face of the punch-backing part, and a die plate carried by said support, said die plate being notched to provide a pair of laterally spaced arms which embrace the said

punch-backing part and have integrally formed elements at their free ends which interlock with the die support to prevent planar displacement of the rear end of the die plate relatively to said reciprocating punch.
